DOOR CHECK AND CLOSER

Rexford C. Van De Boe, Drexel Hill, Pa.

Application April 12, 1946, Serial No. 661,683

7 Claims. (Cl. 16—49)

1

This invention relates to door checks and closers, more particularly to checks and closers of the mechanical type as distinguished from the more common hydraulic or pneumatic types, and has for an object to provide improved apparatus of this character.

Another object of the invention is to provide a mechanical door check and closer wherein a spring or equivalent means acts upon an open door to close the same, and a brake means prevents too rapid closing of the door and slows its closing motion almost to a stop momentarily when the door is nearly closed.

A further object of the invention is to provide a novel door check and closer of the mechanical type having an internal expanding brake member, together with means for causing said brake to retard closing movement of a door and to offer little or no resistance to opening of said door.

Yet another object of the invention is to provide a mechanical door check and closer including eccentric mechanism for momentarily retarding the rate of closing of the door controlled by said check and closer.

These and other objects are effected by the invention as will be apparent from the following description and claims, taken in accordance with the accompanying drawings, forming a part of this application, in which:

Fig. 1 is a fragmentary perspective view of a door casing and door equipped with a door check and closer constructed in accordance with the present invention;

Fig. 2 is a top plan view of the door check and closer of Fig. 1;

Fig. 3 is a side elevational view of the mechanism shown in Figs. 1 and 2;

Fig. 4 is a bottom plan view of the mechanism of the preceding figures;

Fig. 5 is a plan view, with a portion of the structure broken away along the line V—V of Fig. 6, looking in the direction indicated by the arrows;

Fig. 6 is a sectional view, taken along the line VI—VI of Fig. 2, looking in the direction indicated by the arrows;

Fig. 7 is a sectional view, taken along the line VII—VII of Fig. 2, looking in the direction indicated by the arrows;

Fig. 8 is a perspective view of a pair of co-operating elements of the mechanism of the preceding figures; and,

Fig. 9 is a plan view of yet another element of the mechanism.

Referring now to the drawings in greater detail,

2

the reference character 10 indicates, in its entirety, a check and closer for a door 11, hinged, as at 12, to the door casing 13.

The closer 10 includes a housing or casing 14, whose side wall 16 is cylindrical. A bottom wall 17, integral with the side wall 16, is permanently secured to a supporting angle or bracket 18 in any suitable manner, for example, by spot welding. The leg 19 of the bracket 18 is provided with openings 21 for passage of screws by which the closer is secured to the door 11 in the usual manner.

The open top of the casing 14 is adapted to be closed by a removable cover 22, retained in closing relation to the casing 14 by a plurality of screws 23. The cover 22 is provided with a flanged axial opening 24, the flange 26 thereof serving as a bearing for a hub 27, rotatably mounted therein and prevented from withdrawal therefrom by a hub flange 28 abutting the inner side of the cover 22.

The hub 27 has a portion 29 of non-circular cross section adapted to be closely received in a mating opening 31 in a lever 32, and to be retained therein by nut 33 threaded on stud 34, integral with the outer end of hub 27. Thus, the hub 27 and the lever 32 will move as a unit.

The free end of lever 32 has a ball 36 projecting from its upper surface and adapted for reception in a mating socket member 37 carried at one end of a link 38, whose length is adjustable through the threaded connection, at 39, of the two parts 41 and 42 thereof. The free end of part 42 is adapted to be pivotally attached to the door casing 13 by the bracket 43 and pin 44, in the usual manner. It will be apparent that opening of the door 11 will operate through link 38 and lever 32 to rotate the hub 27 in a clockwise direction relative to the casing 14, as viewed in Figs. 1, 2 and 5, and that closing of the door will be accompanied by counterclockwise rotation of the hub relative to the casing.

The inner surface of the circular casing side wall 16 serves as a brake drum against which bears a brake band 46 of suitable braking material. The brake band 46 is secured to the outer surface of a resilient carrier or brake shoe 47 by a plurality of rivets or screws 48. The brake band 46 is of a length somewhat less than a full circle, and the resiliency of the brake shoe 47 is such as to normally urge the brake band outwardly into engagement with the drum surface of the casing side wall 16. One end of the brake shoe 47 is turned back upon itself, as at 49, to provide a loop 51 for passage of a pin 52 carried by the spaced

3
ends of a pair of parallel arms 53 and 54 of a brake-driving member 56. The opposite ends of the arms 53 and 54 are joined by a post 57, integral therewith.

The upper arm 53 of the brake-driving member 56 is provided with a non-circular opening 58 for mating reception of a correspondingly-shaped portion at the inner end of the hub 27. The arm 53 abuts the inner surface of the hub flange 28 and is retained in position by suitable means, for example, by peaning the inner end of the hub 27, as at 59. Consequently, rotation of the hub 27 relative to the casing 14 will produce corresponding rotation of the brake-driving member 56 and the brake band 46.

It will be apparent, upon consideration of Fig. 5, that clockwise rotation of the brake band, with the rotative force applied as a pull at the pin 52, will tend to effect a reduction in the diameter of the brake band, thereby reducing its frictional engagement with the brake drum. As this clockwise rotation occurs upon opening of the door 11, it will be seen that the brake band offers little or no resistance to such opening.

When the brake-driving member 56 and its associated hub 27 and lever 32 rotate in a counterclockwise direction to close the door, the brake band is pushed counterclockwise with the pushing force applied at the pin 52, thereby tending to expand the brake band and increase its frictional engagement with the brake drum, with the result that rapid closing of the door is resisted by the friction of the brake band and drum.

A central shaft 61 has its lower end rotatably received in aligned openings 62 and 63 in the casing bottom wall 17 and the bracket 18, respectively, and has its upper end rotatably received in a mating bore 64 provided in the inner end of the hub 27.

The hub 27 and shaft 61 are at all times free to rotate relative to each other, but the shaft is normally secured against rotation relative to the casing 14 and its supporting bracket 18 by insertion of a plug 66 in an opening 67 formed partially in the end of the shaft 61 and partially in the casing bottom wall 17 and adjacent bracket 18 (Figs. 4 and 7). Preferably, the casing bottom wall and the supporting bracket are provided with a plurality of semi-circular openings 68 adapted to register with the mating half opening 67 in the shaft 61 when the latter is moved to various positions of rotation, for a purpose to be explained later.

The shaft 61 is slotted longitudinally, as at 81, for reception of the inner end 82 of a coil spring 83. The outer end of the spring 83 is bifurcated, as at 84, to provide a pair of spaced arms 86 of hooklike configuration, for engagement with the terminal portions 87 of a pin 88, projecting from opposite sides of a spring-retaining plate 89, through a hole 90 therein (Figs. 5, 6 and 9). This plate 89 has an opening 91 therein whose walls are adapted to act as a retainer for the coil spring 83, to limit its expansion. The pin 88 extends through the plate near the opening 91, with the slot or bifurcation 84 in the outer end of the spring receiving the portion of the plate which lies between the openings 90 and 91 (Fig. 6).

The spring-retaining plate 89 has an opening 92 therethrough, in its end 93, for passage of the pin 52. Consequently, any rotative movement of the brake band 46 is accompanied by corresponding movement of the spring-retaining plate 89, and vice versa.

The plate 89 has one corner of its end 93

shaped to provide a shoulder 94, normally spaced slightly from the adjacent end 96 of the brake band 46. If, when the door is opened and the brake band is moved clockwise, as viewed in Fig. 5, the end 96 of the brake band tends to stick or drag, the shoulder 94 of the spring-retaining plate will engage it and push it around. However, before the shoulder 94 and the brake band end 96 engage, the other end of the brake band will have moved far enough to have contracted the brake band to an extent sufficient to prevent its engaging the brake drum with enough frictional force to interfere with free opening of the door.

15 The mechanism thus far described operates substantially as follows: As the door 11 is moved from closed to open position, the lever 32, hub 27, brake-driving member 56 and pin 52 will rotate clockwise, as viewed in Fig. 5, as a unit relative to the casing 14, its supporting bracket 18 and the shaft 61, which remain relatively stationary as a unit. This clockwise rotation of the pin 52 will pull the brake band 46, attached thereto by its brake shoe 47, clockwise along the inner 20 surface of the casing side wall 16. This pulling force applied to the brake band at the end thereof of adjacent the pin 52 will tend to contract the brake band, thereby reducing its friction against the brake drum and permitting unopposed opening of the door. As the pin 52 moves clockwise, the spring-retaining plate 89 through which it passes will likewise be rotated clockwise, and the outer end of the coil spring 83, attached to plate 30 89 by the pin 88, will be moved to increase the 35 normal tension thereof and to store up additional energy therein.

When the opened door is released, the energy in the coil spring 83 acts through the spring-retaining plate 89 to move the pin 52, brake-driving member 56, hub 27 and lever 32 in the opposite, or counterclockwise, direction to close the door 11. The brake band 46 is likewise pushed in counterclockwise direction by the pin 52, and the application of this pushing force at the end 45 of the brake band adjacent the pin 52 tends to expand the brake band, thereby causing it to drag on the brake drum 16 with sufficient friction to prevent too rapid closing of the door.

It has frequently been found desirable to apply momentarily an extra retarding action to the closing motion of the door when it is about a foot from closed position, to insure that it does not slam when latching. The present invention includes additional mechanism, now to be described, for performing this function.

Referring particularly to Figs. 5 and 8, a flat spring 101 is secured at one end, by rivet 48, to the brake band 46 and brake shoe 47, and has its other end engaging the inner surface of the brake shoe. Intermediate its ends the flat spring 101 is secured by rivet 102 to a post 103 formed integral with, and joining, a spaced pair of upper and lower arms 104 and 105, respectively; the post 103 and arms 104 and 105 constituting the follower member 106. The spacing of the arms 104 and 105 is such as to permit their being positioned in straddling or overlapping and underlying relation to the arms 53 and 54 of the brake-driving member 56, with freedom of movement relative thereto.

Inasmuch as the follower member 106 is secured to the brake band and brake drum by the flat spring 101 and the rivets 48 and 102, it turns with the brake band. The arms 104 and 105 have aligned circular openings 107 therein bounded

by outwardly-extending flanges 108. These flanges 108 are adapted to surround and ride upon mating inwardly-directed flanges 109 at the peripheries of upper and lower eccentrics 110 and 111, respectively, fixedly secured to the casing cover 22 and the casing bottom wall 17, respectively. These eccentrics are directly opposed, and are offset laterally with respect to the axis of the casing side wall or brake drum 16. As the door 11 moves from open to closed position, the follower member 106 will rotate relative to, and be guided by, the eccentrics 110 and 111. As the post portion 103 of the follower member passes the high points of the eccentrics, it will be moved radially outward with consequent increase in the pressure exerted on the brake band by the flat spring 101, this additional braking action further retarding the closing motion of the door. The eccentrics are so disposed that this additional braking action takes place shortly before the door reaches closed position. After the post portion 103 of the follower member has passed the high points of the eccentrics, the closing motion of the door will return to its previous speed, which will be sufficient to assure positive latching of the door.

Adjustment of the tension in the coil spring 83, to increase or decrease the closing force, is effected by inserting a socket screw wrench in the hexagonal opening 115 in the bottom end of the shaft 61, removing the locking plug 66, and turning the shaft in the desired direction to change the spring tension. The shaft is secured in its new position of adjustment by inserting the locking plug 66 in one of the openings formed by the half opening 67 in the shaft 61 mating with one of the half openings 68 in the casing bottom wall 17 and the bracket 18. The four half openings, spaced ninety degrees apart, provide for quarter-turn adjustment of the shaft and spring.

While the invention has been shown in but one form, it will be apparent that it is not so limited, but is susceptible of various changes, modifications and applications without departing from the spirit thereof.

What is claimed is:

1. In a door check and closer, a casing including a circular side wall whose inner surface is adapted to function as a brake drum, a shaft extending axially of said drum, means securing said shaft against rotation relative to said drum, a brake band within said casing and adapted to frictionally engage said drum, means normally urging said brake band into frictional engagement with said drum, means for rotating said brake band relative to said drum in one direction upon opening of a door with which said check and closer is associated, and a coil spring having one end secured to the shaft and the other end operatively associated with said last-mentioned means, whereby said spring is tensioned upon opening of the door and whereby said tensioned spring operates through said last-mentioned means to close the door and to rotate the brake band relative to the drum in the opposite direction, said last-mentioned means including means for reducing the normal frictional engagement of the brake band with the drum during opening of the door and for increasing said normal frictional engagement during closing of the door.

2. In a door check and closer, a brake drum; a brake band adapted to rotate relative to said drum in one direction when a door with which said check and closer is associated is moved to

open position and to rotate in the opposite direction relative to said drum when the door is moved to closed position; first means associated with said brake band and adapted to maintain the latter in light frictional engagement with the drum while the door is being opened and to urge the brake band into heavy frictional engagement with the drum when the door is being closed, whereby opening movement of the door

10 is unretarded by the brake and closing movement is retarded to prevent slamming; and second means associated with said brake band for biasing the latter against the brake drum with predetermined pressure throughout the first and major portion of the closing movement of the door, said second means being eccentrically mounted for movement with the brake band, said eccentric mounting providing for increase in the braking action as the door nears its closed position and for thereafter decreasing said braking action before completion of the door-closing motion.

3. In a door check and closer, a casing including a circular wall whose inner surface is adapted to function as a brake drum; a brake band adapted to rotate relative to said inner surface in one direction when a door with which said check and closer is associated is moved to open position and to rotate in the opposite direction relative to said inner surface when the door is moved to closed position; a spring in the form of a strip of resilient material associated with said brake band at the side thereof away from said inner surface and adapted to maintain the brake band in light frictional engagement with the drum while the door is being opened and to urge the brake band into heavy frictional engagement with the inner surface when the door is being closed, whereby opening movement of the door is unretarded by the brake and closing movement is retarded to prevent slamming; a shaft disposed axially of said casing; means preventing relative rotation of said shaft and casing; a coil spring having one end secured to said shaft and the other end operatively associated with said brake band, whereby upon opening movement of the door said spring is tensioned and the energy thereby provided in said spring functions to produce closing movement of the door.

4. In a door check and closer, a casing including a circular wall adapted to function as a brake drum; a shaft within said casing disposed axially of said circular wall and normally non-rotatable relative thereto; a brake band within said casing and adapted to rotate in one direction relative to said drum when a door with which said check and closer is associated is moved to open position and to rotate in the opposite direction relative to said drum when the door is moved to closed position; a coil spring surrounding said shaft in spaced relation to the walls of said casing and having its inner terminal portion secured to said shaft and its outer terminal portion operatively associated with said brake band, whereby during opening movement of the door the normal tension of said spring is increased and said increased tension functions to produce the closing movement of the door; a centrally-disposed hub rotatably mounted in and extending through the top wall of the casing; an operating lever carried by the outer end of said hub; a U-shaped brake-driving member disposed horizontally in the casing with the upper leg thereof overlying the coil spring and non-rotatably secured to the inner end of said hub and the lower leg underlying the

coil spring in parallel spaced relation to the upper leg; and means securing the free ends of said legs to the brake band, whereby movement of said lever is imparted to said brake band, and movement of the latter is transmitted to said lever.

5. In a door check and closer, a brake drum; a brake band adapted to rotate in one direction relative to said brake drum when a door with which said check and closer is associated is moved to open position, and to rotate in the opposite direction relative to said drum when the door is moved to closed position; a coil spring having one end connected with said drum and the other end connected with said brake band, said spring normally being tensioned and said tension being increased upon rotation of said brake band relative to said drum in said one direction upon opening of said door, and said increased spring tension constituting a source of power for closing the door; an eccentric stationary relative to said drum; a follower connected to and rotatable with said brake band and adapted to be moved radially by said eccentric upon rotary movement relative thereto, outward radial movement of said follower operating to increase the frictional engagement of the brake band with the drum, thereby retarding closing action of the door; and said eccentric being so disposed with respect to the path of travel of said follower and brake band that maximum retardation of the door-closing action occurs as the door nears its closed position.

6. In a door check and closer, casing structure including a circular wall defining a brake drum; a brake band adapted to rotate in one direction relative to said brake drum when a door with which said check and closer is associated is moved to open position and to rotate in the opposite direction relative to said drum when the door is moved to closed position; a hub rotatable with respect to said casing structure; a lever disposed exteriorly of said casing structure, said lever being operatively associated with said hub and moved relative to said casing structure, and means connecting said lever to said hub, whereby movement of said lever is imparted to said hub, and movement of said hub is transmitted to said brake band.

tive to said casing structure upon movement of the door; a brake-driving member housed in said casing structure and providing a driving connection between said hub and said brake band; a shaft normally non-rotatable relative to said casing structure; a coil spring surrounding said shaft and having one end secured thereto; means providing a driving connection between the other end of said spring and the brake band, whereby rotation of said brake band in said one direction relative to said drum in response to opening of the door contracts said spring, and the tension in said contracted spring rotates said brake band in said opposite direction relative to the drum to close the door; an eccentric carried by said casing structure; and a follower carried by said brake band and moved radially by said eccentric during rotation of said brake band, outward radial movement of said follower increasing the frictional contact of said brake band with said drum and thereby retarding closing action of said door.

15 7. Structure as specified in claim 6, wherein said brake band is less than a full circle in length and said brake-driving member is connected thereto adjacent one end thereof, whereby upon opening of the door said one end of the brake band is pulled toward the other end thereof with reduction in the diameter of said band, and upon 20 closing of the door said one end of the brake band is pushed away from the other end thereof with increase in the diameter of said band.
